(57) **CLAIM**

The ornamental design for a bicycle shoe strap, substantially as shown and described.

DESCRIPTION

FIG. 1 is a perspective view of a bicycle shoe strap positioned across a throat of an exemplary bicycle shoe;

FIG. 2 is a top plan view of the bicycle shoe strap of FIG. 1; FIG. 3 is a lateral right side elevation view of the bicycle shoe strap shown in FIG. 1;

FIG. 4 is lateral left side elevation view of the bicycle shoe strap shown in FIG. 1;

FIG. 5 is a longitudinal side elevation view of the bicycle shoe strap shown in FIG. 1; and,

FIG. 6 is a bottom plan view of the bicycle shoe strap shown in FIG. 1.

The broken lines represent environmental structure and portions of the shoe strap that form no part of claimed design.
